DESIGN FOR A SHOE

Moise Lichtentag, New York, N. Y.

Application October 21, 1939, Serial No. 87,788

Term of patent 7 years

To all whom it may concern:

Be it known that I, Moise Lichtentag, a citizen of the United States and residing in Manhattan, in the city, county, and State of New York, have invented a new, original, and ornamental Design for a Shoe, of which the following is a specification, reference being had to the accompanying drawing, forming part thereof, wherein

Fig. 1 is a plan view of a shoe showing my new design.

Fig. 2 is a side perspective view thereof.

My design concerns the vamp portion of a shoe and embodies a drill or canvas surface surrounded by an unstitched rim of other material contrastingly colored, said revealed under surface, while appearing to be the outer surface, is actually the back of the inside material, commonly known and referred to as the lining of the shoe.

I claim:

The ornamental design for a shoe, as shown and described.

MOISE LICHTENTAG.
